UNITED STATES PATENT OFFICE

2,619,334

CARBURETOR FOR AIRCRAFT ENGINES
WITHOUT COMPRESSORS

Roger H. Tissier, Paris, France, assignor to Societe Nationale d'Etude et de Construction de Moteurs d'Aviation, Paris, France, a French company

Application April 2, 1949, Serial No. 85,142
In France April 2, 1948

4 Claims. (Cl. 261—47)

1

The carburetors for aircraft engines without an air compressor should meet certain requirements:

1. For the comparatively high air inlet pressures (on take off, or rated engine running), that is near the atmospheric pressure at ground level, the air-gasoline mixture provided by the carburetor should be rich.

2. For the cruising load, the pilot should be able to obtain either a mixture giving an economical consumption, or, during a temporary period of strenuous working of the engine (for instance during climbing) a comparatively rich mixture.

3. Finally, it may be useful, chiefly in the case of engines without air compressor, to be able to obtain the maximum power of the engine at any altitude, that is to pass from the economical mixture to the mixture corresponding to the maximum power.

If the carburetor is provided for manual altimetric correction, these requirements may be achieved at the cost of imposing an additional duty on the pilot. Moreover, this may lead to overstrain of the engine in case the pilot, lacking experience in handling the control, sets the latter in a position corresponding to too weak a mixture.

If the carburetor is arranged for automatic altimetric correction, it is convenient to be able to use a supplementary manual control in order to pass from the economical mixture to the maximum power or climbing mixture.

In other words, in an engine without air compressor, under otherwise equal conditions, the downstream pressure with respect to the butterfly or throttle-control depends on the altitude and on the pressure-loss due to the butterfly position.

The present invention has for its object to provide an adjusting device to obtain automatically the resultant of both these factors on the carburetor mixture and which can be conveniently combined with a manual correcting means available to the pilot, thus providing a richness suitable to each admission pressure, both at altitude and on the ground, without requiring an admission pressure diaphragm.

This device comprises a link between the throttle-lever (or the butterfly) and the altimetric adjusting needle or valve operated by means of the altimetric-control box.

Other objects and advantages of the invention will be apparent during the course of the following description.

In the accompanying drawing forming a part of this application and in which like numerals

2

are employed to designate like parts throughout the same,

Figures 1 to 3 are diagrammatic cross-sections of three embodiments of the invention which may be applied to every aircraft engine without compressor, whatever its principle.

These embodiments permit automatic enrichment for high admission pressures at ground level, as well as for full-throttle running up to the altitude corresponding to the admission pressure necessitating enrichment. Moreover, they allow, for an operating condition other than high admission pressure conditions, automatic operation either with a weak mixture or with a rich one.

In the drawings, for convenience, the butterfly or air throttle 10 has been separated from the carburetor whose choke tube or venturi forming the mixing space is in 10a, but obviously, the air throttle is located as usual either in front, or behind this venturi. The engine is in M; it sucks air through the tube 2 and venturi 10a. The atmospheric air is in A.

In the embodiment shown in Fig. 1 an emulsifier 1 receives the liquid fuel as usual from a constant level container, not shown, which is connected to the emulsifier through a duct 1a. Said emulsifier receives further air through a channel 1b originating at 1c upstream with respect to the nozzle 10a, so that the pressure of said air is the atmospheric one.

The exit 1d of said emulsifier being connected to ports 10b provided in the restricted zone of the venturi 10a, the suction generated in said zone by the air stream is transmitted through said ports to the said exit of the emulsifier. Consequently air and fuel are sucked in through said emulsifier and form a primary mixture (emulsion) which is finally admitted through ports 10b into the air flowing through nozzle 10a.

Carburetors of this kind are well known. It is also known to regulate the richness of the final mixture in nozzle 10a in the following manner:

45 A channel 9a communicating with port 1c and channel 1b is connected with the exit 1d of the emulsifier through a calibrated aperture controlled by a needle-valve 4 controlled in its turn by a pressure responsive box 5, the outline of this needle 4 being adapted to alter the area of flow 50 section between the wall of the aperture or seat 3 and the needle 4, according to the altitude.

The proposed improvement comprises the following arrangements:

The altimetric adjusting needle-valve 4 is 55 provided with a cylindrical extension 6 on which

a sleeve 7 freely slides, its displacement being controlled by a lever 8. The needle is hollow and pierced with ports 9, at a convenient height, on its cylindrical portion and also with ports 9b under the seat 3. Thus, through the duct 9a, through ports 9 whose sizes are predetermined during adjustment and through ports 9b, a connection is established between the air-channel 2 and the exit of the emulsifier 1, thus causing a drop in the suction over the emulsifier, and hence, a leaning of the mixture.

According to its position, the sliding sleeve 7 covers or uncovers the calibrated ports 9.

The control of the position of this sleeve 7 is effected automatically by the rotation of the butterfly 10. For this purpose, a cam 11 is keyed to the axle 10c of butterfly 10, in such a way as to turn at the same time as that butterfly when the throttle-control is operated. On this cam is applied a roller 12a carried at the end of a connecting rod 12 hinged on lever 8. This lever pivots about a fixed point 8a and is submitted to the action of a spring 8c which applies permanently the roller 12a on the cam 11. The connecting rod 12 is guided on the butterfly axle 10c by means of a slot 12d which this axle crosses. In the drawing, cam 11 as well as connecting rod 12 are shown inside the suction-duct of the engine. In practice, these members are outside this duct, cam 11 being keyed to an extension of the butterfly axle 10c.

The device described causes the sleeve 7 to move along the extension 6 of the needle 4 when the butterfly or throttle-control is operated, the position of sleeve 7 depending therefore on that of the butterfly.

During operation at ground level and starting with a certain opening of the butterfly 10, the sliding sleeve 7 closes ports 9 of the adjusting needle 6; the maximum richness is achieved when the ports are entirely closed (the butterfly is wide open).

If it is now assumed that the aircraft takes off with the butterfly wide open, then as the aircraft climbs, the altimetric-control diaphragm 5 lengthens and causes the ports 9 to be uncovered, thus lowering progressively the richness while the inlet pressure decreases.

Thus, at ground level and at altitudes, a mixture proportional to the inlet pressure is achieved.

Moreover by acting on lever 8 through a manual control, not shown, connected to the end 8b of lever 8, it is always possible to set sleeve 7 at its upper position, whatever the altitude, so that ports 9 are closed and the mixture enriched.

It is thus possible, by means of this manual control to feed the engine either with a weak mixture (economic cruising rating), or with a rich one (climbing, maximum power in altitude, etc.)

The embodiment shown in Fig. 2 is of the type with altimetric adjustment through decrease in pressure above the level of the fuel in the float chamber 14 which supplies the jet 1. The device is similar to the previous one and the operation identical, but the adjustment is achieved by connecting the neck of the venturi 10a to the upper part of the chamber 14 through duct 9a, seat 3 controlled by needle 4 and ports 9 controlled by sleeve 7.

Over the fuel in chamber 14, a pressure less than atmospheric and determined according to the altitude by the position of the altimetric adjusting needle 4, is thus created.

The third embodiment shown in Fig. 3 is of

the type with altimetric adjustment by reducing the flow of gasoline, the adjusting needle 4 operated by the pressure responsive box 5 acting on the gasoline flow supplying the jet 1 from container 14 through ports 3 and 9 and duct 15.

On this needle is arranged the sliding sleeve 7 operable to cover or uncover one or more ports 9 connecting, through the inner cavity of needle 4, container 14 and duct 15 of the emulsifier. 10 The device is such that these ports 9 are wholly or partly uncovered for high air inlet pressures, while they are covered for low air inlet pressures owing to the action of the pressure responsive box 5.

15 As above, it is further possible to arrange a manual control for operation with either weak or rich mixtures.

The advantages of the invention are as follows:

20 1. Automatic regulation of the richness for high air inlet pressures with a single atmospheric pressure responsive box, the action of which is combined with that of sleeve 7 and ports 9 according to the aperture of the air throttle, enabling to obtain simultaneously the altimetric adjustment and a richness varying according to the air inlet pressure.

2. Possibility to operate automatically with a very economical adjustment (weak mixture).

3. Possibility to have the maximum engine power available at altitudes by the operation of the primer (rich mixture-ratio).

25 4. Possibility to increase the richness for high power ratings required from the engine (climbing for instance).

30 What I claim is:

1. In a carburetor for an aircraft engine without compressor having a movable air throttle and a mixing space, two valve devices arranged in 40 parallel relationship to control independently from one another the fuel supply to the mixing space, one of said valve devices being adapted to reduce the fuel supply in response to a decrease in atmospheric pressure and conversely, while the other valve device includes two valve members arranged to move independently with respect to one another, one of said members being adapted to reduce the fuel supply in response to a decrease in atmospheric pressure and conversely, and means for connecting operatively the other member to the throttle, said means being adapted to move said other member towards its fuel supply increasing position when the throttle is open and conversely.

55 2. In a carburetor for an aircraft engine without compressor, having a movable air throttle and a mixing space, a regulating device for the fuel supply to said mixing space comprising a fuel supply control passageway, a stationary seat provided in said passageway, a movable needle the outer surface of which is adapted to cooperate with said seat in order to vary the cross-section area of said passageway, means sensitive to the atmospheric pressure operatively connected to 60 said needle and adapted to move it with respect to said seat so as to reduce the fuel supply in response to a decrease in atmospheric pressure and conversely, said needle being provided with an internal cavity and with lateral ports adapted to 65 connect said cavity respectively with the ports of said passageway located on each side of said seat so as to form a second fuel supply control passageway arranged in parallel relationship with respect to the first-named passageway, a sleeve 70 connect said cavity respectively with the ports of said passageway located on each side of said seat so as to form a second fuel supply control passageway arranged in parallel relationship with respect to the first-named passageway, a sleeve slidably mounted on said needle so as to control

its ports on one side of said seat, and means mechanically connecting said sleeve to said movable air throttle, said means being adapted to move said sleeve with respect to the corresponding needle ports towards the fuel supply increasing position of said sleeve when the throttle is open and conversely.

3. In a carburetor for an aircraft engine without compressor, having a movable air throttle and a mixing space, an emulsifier the exit of which is connected to said mixing space, an air passageway connected to the atmosphere and to the exit of said emulsifier, two valve devices arranged in parallel relationship in said air passageway to control independently from one another the cross-section area of said air passageway, one of said valve devices being adapted to increase the cross-section area of said air passageway in response to a decrease in atmospheric pressure and conversely, while the other valve device includes two valve members arranged to move independently with respect to one another, one of said members being adapted to increase the cross-section area of said air passageway in response to a decrease in atmospheric pressure and conversely, and means for connecting operatively the other member to the said throttle, said means being adapted to move said other member towards its cross-section area reducing the position when the throttle is open and conversely.

4. In a carburetor for an aircraft engine without compressor, having a movable air throttle and a mixing space, an emulsifier the exit of which is connected to said mixing space, an air passageway connected to the atmosphere and to the exit of said emulsifier, a stationary seat provided in said air passageway, a movable needle the outer surface of which is adapted to cooperate

with said seat in order to vary the cross-section area of said air passageway, means sensitive to the atmospheric pressure operatively connected to said needle and adapted to move it with respect to said seat so as to increase the cross-section area of said air passageway in response to a decrease in atmospheric pressure and conversely, said needle being provided with an internal cavity and with lateral ports adapted to connect said cavity respectively with the ports of said passageway located on each side of said seat so as to form a second air passageway arranged in parallel relationship with respect to the first-named passageway, a sleeve slidably mounted on said needle so as to control its ports on one side of said seat, and means mechanically connecting said sleeve to said movable air throttle, said means being adapted to move said sleeve with respect to the corresponding needle ports towards the ports opening position of said sleeve when the throttle is open and conversely.
